[57] CLAIM

The ornamental design for the brassiere, substantially as shown and described.

DESCRIPTION

FIG. 1 is a flattened view of the outside of a brassiere showing my new design;

FIG. 2 is a flattened view of the inside;

FIG. 3 is a front perspective view;

FIG. 4 is a view like FIG. 1 of a modified form of a brassiere showing my new design, wherein the side and bottom front panels below the cups are plain;

FIG. 5 is a flattened view of the inside of the FIG. 4 brassiere; and

FIG. 6 is a front perspective view thereof.
